HANDLE AND LATCH UNIT FOR SLIDING DOOR

Harry M. Riegelman, Rolling Hills, and Oscar Altman,
Hollywood, Calif., assignors to Holiday Door Corporation,
Gardena, Calif., a corporation of California

Filed June 1, 1959, Ser. No. 56,152

Term of patent 3½ years

(Cl. D10—8)

Fig. 3

We claim:

The ornamental design for a handle and latch unit for sliding door, substantially as shown.
